UNITED STATES PATENT OFFICE.

NELS R. CLIFTON, OF DULUTH, MINNESOTA.

RECEPTACLE.

1,218,524.

Specification of Letters Patent.

Patented Mar. 6, 1917.

Application filed August 17, 1916. Serial No. 115,447.

To all whom it may concern:

Be it known that I, NELS R. CLIFTON, a citizen of the United States, residing at Duluth, in the county of St. Louis and State of Minnesota, have invented certain new and useful Improvements in Receptacles; and I do declare the following to be a full, clear, and exact description of the invention, such as will enable others skilled in the art to which it appertains to make and use the same.

This invention relates to new and useful improvements in receptacles, such as cans and the like for holding tobacco, and the primary object is to provide the receptacle with a longitudinally adjustable bottom for holding the tobacco in such a position that access may be easily had thereto as it is discharged from the receptacle.

Another object of this invention is to provide a device of this character which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claim.

In the accompanying drawing:

Figure 1 is a vertical longitudinal section showing my device applied;

Fig. 2 is a vertical transverse section on the line 2-2 of Fig. 1;

Fig. 3 is a horizontal section on the line 3-3 of Fig. 1; and

Fig. 4 is a detail perspective view of the sliding bottom.

In the present embodiment of my invention, I have illustrated in the accompanying drawing a tobacco can of the conventional type which is used for carrying smoking tobacco. The can comprises a casing 1 which has open ends, the upper end being provided with a hinged cover 2, while its lower end is provided with an inwardly projecting flange 3 which extends a short distance from the edge. The casing 1 may be of any desired shape, but in the accompanying drawing, I have shown the same to be of the conventional shape, which shows the same to be of a slight width.

When a portion of the contents of a receptacle of this character is removed, the sur-

face of the tobacco will be below the level of the top of the receptacle, and the user is liable to injure his fingers in thrusting them into the narrow space between the sides. The sharp edges of the can or receptacle body are liable to cut the fingers, in addition to making it extremely difficult to remove the proper amount of tobacco.

To overcome these objections, I have provided the casing 1 with a sliding bottom 4 which comprises a plate having its outer edges 5 conforming substantially to the shape of the interior of the casing. This bottom plate 4 is slidably mounted within the casing, and is adapted to freely move longitudinally with respect thereto. The inturned flange 3 at the bottom of the casing will prevent the bottom from dropping therefrom, and will also form a rest and stop for the bottom when the casing is full.

The side edges 5 of the sliding bottom plate are provided with a plurality of upwardly extending spaced fingers 6 and 7. The spaced fingers 6 are disposed at the opposite ends of the plate, and conform substantially to the rounded opposite sides of the casing. The fingers 7 are flat and are spaced at opposite points along the side edges of the bottom as clearly shown in Fig. 4 of the drawing. This bottom plate 4 with the upturned fingers 6 and 7, are all preferably formed integrally, of sheet metal, and the fingers will consequently be slightly flexible, and will be adapted to move into and out of tight frictional engagement with the inner wall of the casing.

The fingers 6 and 7 of the bottom plate are of sufficient height and width so that when the casing is filled, the contents thereof, when brought into engagement with these fingers, force the same outwardly against the adjacent inner wall of the casing. The contents of the casing may be either tobacco wrapped in paper cartons, or loose tobacco compressed. However, material placed therein under sufficient pressure will, owing to the construction of these fingers, force them outwardly for the aforesaid purpose. This frictional engagement with the inner wall of the casing while not in any way preventing the bottom plate from sliding longitudinally within said casing, will prevent any undue movement of the same, and allow the bottom plate to be adjusted in various longitudinal positions.

along the casing. In addition to this, the fingers will also prevent the bottom from tilting.

As the tobacco, when this receptacle is used as a tobacco can, is removed or poured from the upper end of the casing, and it is desired to force the remaining contents toward the top so that it will be easily accessible, it will be only necessary to move the 10 sliding bottom plate 4 upwardly the required distance, and owing to the frictional engagement of the fingers with the inner wall of the casing, the bottom will be held in such position. This overcomes the necessity of 15 digging into the can, and injury to the user's fingers in attempting to reach tobacco which is well down in the casing, is prevented.

This longitudinally adjustable sliding bottom will also be prevented from tilting by the spaced fingers on the outer edge of the same, and will always be disposed across the bottom of the casing. It will be impossible for the bottom to drop therefrom, 25 owing to the inwardly projecting flange 3 at the lower end of the casing. The casing may be of any desired shape, it only being necessary that the sliding bottom conform to the same shape, and be provided with the 30 upwardly projecting fingers of sufficient width to permit the aforesaid frictional engagement when the device is in operation.

From the foregoing description of the construction and operation of my improved

tobacco receptacle, the manner of applying 35 the same to use, and the operation thereof will be readily understood, and it will be seen that I have provided a simple and efficient device of this character for carrying out the objects of the invention. 40

I claim:

A device of the class described comprising a casing having open ends, an inwardly projecting flange on the lower edge of said casing, a movable bottom in said casing comprising a plate with its edges snugly engaging the inner wall of said casing, and upwardly projecting integral spring fingers on said edges at each end and on opposite sides of the plate, said fingers being of a width 45 and height to afford a sufficient flexible engagement between their outer faces and the inner wall of the casing to hold the plate normally stationary, said engagement being made continuous by the outward pressure 50 exerted on the inner faces of the fingers by the closely pressed contents of the casing, whereby the plate may be longitudinally adjusted in the casing and will be prevented from tilting when moved. 55

In testimony whereof I have hereunto set my hand in the presence of two subscribing witnesses.

NELS R. CLIFTON.
